(57) **CLAIM**

The ornamental design for a razor as shown and described.

DESCRIPTION

FIG. 1 is a top front isometric view of a razor showing the claimed design;

FIG. 2 is a top rear isometric view thereof;

FIG. 3 is a left side elevation view thereof, the right side elevation view being a mirror image thereof;

FIG. 4 is a front elevation view thereof;

FIG. 5 is a left side elevation view thereof showing the razor in a state in which it may be used; and,

FIG. 6 is a front perspective view thereof showing the razor in a state in which it may be used.

The dashed broken lines in the figures show portions of the razor that form no part of the claimed design.

The dot-dash broken lines in the figures show boundaries that form no part of the claimed design.

1 Claim, 6 Drawing Sheets
